US0D1054897S

(12) **United States Design Patent** (10) **Patent No.:** **US D1,054,897 S**
(45) **Date of Patent:** **** Dec. 24, 2024**

(54) **BARRICADE**

(71) Applicant: **Neubert Aero Corp.**, Tampa, FL (US)

(72) Inventor: **Timothy W. Neubert**, Tampa, FL (US)

(73) Assignee: **Neubert Aero Corp.**, Tampa, FL (US)

(**) Term: **15 Years**

(21) Appl. No.: **29/956,911**

(22) Filed: **Aug. 9, 2024**

(51) LOC (14) Cl. **10-05**

(52) U.S. Cl.

USPC **D10/113.3**

CLAIM

The ornamental design for a barricade as shown and described.

DESCRIPTION

FIG. 1 is a perspective top view of a barricade showing the claimed design;

FIG. 2 is a perspective bottom view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

(Continued)

The broken lines in the figures show environmental structures that form no part of the claimed design.

1 Claim, 5 Drawing Sheets
